(57) **CLAIM**

The ornamental design for an electronic device as shown and described.

DESCRIPTION

FIG. 1 is a front top perspective view of an electronic device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is an enlargement taken from FIG. 1 thereof.

The broken lines depict portions of the electronic device which form no part of the claimed design.

The dot-dash broken lines show an area of enlargement.

(Continued)

The plurality of circles to the left and right of the keyboard are shown in broken lines.
